UNITED STATES PATENT OFFICE.

GORDON VALENTINE, OF CHICAGO, ILLINOIS.

SPRING-CATCH BOX-FASTENER.

No. 900,241.

Specification of Letters Patent.

Patented Oct. 6, 1908.

Application filed July 27, 1907. Serial No. 385,807.

To all whom it may concern:

Be it known that I, GORDON VALENTINE, a citizen of the United States, residing at Chicago, in the county of Cook and State of Illinois, have invented certain new and useful Improvements in Spring-Catch Box-Fasteners, of which the following is a description, reference being had to the accompanying drawings, forming a part of this specification, in which corresponding letters of reference in the different figures indicate like parts.

The object of my invention is to provide a box or safety receptacle for the temporary reception of articles, which receptacle may be so constructed that it may be automatically locked as a result of placing said articles or goods therein and remain so locked until opened by means of a proper key. I accomplish said object in the manner hereinafter more particularly described and definitely pointed out in the claims.

In the drawings, Figure 1 is a longitudinal, vertical sectional view of a box or receptacle embodying the features of my invention, showing the same as it would appear when unlocked, Fig. 2, is a like view showing the parts as they would appear when the device is locked, and Fig. 3, is a like view of the upper portion of the box and lid, showing the manner in which the key is adapted to operate the lock.

Referring to the drawings, *a* represents generally a box or receptacle which, for the purpose for which it is more especially intended to be used, I prefer to provide with double walls having a dead air-space between them, so that the articles placed therein which it may be found desirable to guard, against extremes of heat or cold may be protected thereby. Said receptacle is provided with a lid *b* which may be hinged or connected thereto in any approved way to permit the same to be opened and closed.

Placed above the bottom *c*, of the receptacle in its preferred form, is a false bottom *d* the area of which is enough less than that of the stationary bottom to permit it to be moved up and down without obstruction.

In order to accomplish this movement without binding, I prefer to employ some means for guiding said bottom in its movement.

In the example shown, I have provided pins *e* which are attached to the under side of said movable bottom, preferably near the several corners, and extended downwardly

therefrom into guide holes *f*, formed in the stationary bottom and extending into the blocks or cleats *g*, which are interposed between the walls of the stationary bottom. 60 Coiled springs *h* are arranged to surround the pins *e* and are placed between the movable and stationary parts *d* *c*, for the purpose of normally holding the former in a raised position away from the latter as indicated in Fig. 1,—the strength of the springs being merely sufficient to sustain the weight of said movable bottom and hold the same normally in the position indicated, so that when a weight is placed thereon, said bottom 70 will be caused to descend as shown in Fig. 2. The purpose of this construction is to utilize the downward movement of a movable bottom, whether used with a stationary bottom or not, to actuate a lock, so that the deposit thereon of any article of sufficient weight to induce said movement, will cause the box to be locked when the lid is closed. While I do not wish to be confined to any specific form of lock with which this principle may be utilized, I have shown one which, in its simplicity and effectiveness, is well adapted for the purpose.

Pivoted at *i* upon the inner face and near the upper edge of the front wall of the box, are bent arms or movable guard members, generally designated by *j*, the upper arms of which are provided with hooks *k*, *k*, adapted, when in an abnormal position, to engage counter-hooks or keepers *l*, *l*, which are rigidly attached to the under face of the box lid.

Having its ends attached to the lower ends of the arms *m*, *m*, is a bent spring *n*, which is so constructed and adjusted as to normally separate said arms and hold them apart, as shown in Fig. 1. Said spring is connected through a link *o*, with the false bottom *d* by means of a staple *p*, or otherwise, in such a manner that when said false bottom is in its normal position, the spring is left free to exert its normal action upon the arms *m* and separate them; but when a weight, as *q*, Fig. 2, is placed upon said bottom, a downward tension is placed upon the spring *n* which causes it to draw the arms *m* together as shown in Fig. 2, thereby separating the hooks *k* and holding them in position, respectively, to engage the keepers *l* when the lid is closed. The co-acting members *j* and *l* are beveled as shown, so that when the lid is lowered, if the hooks of the

parts *j* are separated, the keepers will act to force them together until the two pass each other and engage like the parts of an ordinary spring-lock. The arms *m*, of each of which there may be two or more like the guard members of a spring-lock, are cut away as shown at *q*¹ for the reception of a key *r*, Fig. 3, the turning of which may cause said guard members to separate as shown in said last named figure.

The operation of my improved device is as follows: The parts being in the respective positions shown in Fig. 1, the cover may be raised and lowered at will without becoming locked; but as soon as an article is placed in the box so as to rest its weight upon the bottom *d*, the latter is pressed down thereby against the action of the springs *h* and the guard members of the lock are thrown into locking positions by the stress of the spring *n*, so that when the lid is closed, the keepers *l* are engaged thereby, and the lid can only be unlocked by the use of a key.

My improved box is especially intended for use in connection with the delivery of varying kinds of goods or merchandise such, for example, as milk or groceries which are liable to be delivered at the homes of customers during their absence, and left in places where they may be in danger of theft or deterioration by improper exposure. The box is intended to be rigidly secured to some permanent object in a position open to the public and, being normally unlocked, may be opened by anybody. Upon placing any article of weight therein and closing the lid, the article is protected against theft as well as the elements and can only be removed by the person having the key. By this means any article capable of being placed in the box may be protected until removed by the person entitled to its custody.

Having thus described my invention, I claim:

1. A receptacle of the class described having a movable bottom yieldingly held in a normally raised position, a closure, a lock

therefor, said lock being normally held in an unlocking position, and means for moving said lock to a locking position by the depression of said bottom.

2. The combination with a receptacle having a movable supporting element for supporting articles placed therein, said element being yieldingly held in a predetermined normal position, of a closure having means thereon for engaging the guard members of a lock, a lock having a suitable ward, means for normally holding said guard members in an unlocking position and means connected with said movable supporting element for controlling the action of said holding means to permit said guard members to be moved into a locking position when a weight is placed upon said supporting element.

3. The combination with a receptacle having a vertically movable bottom yieldingly supported in a normal position, of a closure having means thereon for engaging the guard members of a lock, a lock consisting of pivoted wards, means for yieldingly holding said guard members in an unlocked position, and means connected with said movable bottom for modifying the action of said holding means to move said guard members to locking positions when the bottom is moved downwardly by the action of a weight thereon.

4. The combination with a receptacle having a vertically movable spring-balanced bottom, of a closure having a keeper thereon for engagement with the guard members of a lock, a lock consisting of guard members pivoted to a stationary point between the ends, hooks upon the upper ends thereof for engaging said keeper, a spring for normally holding said lower ends apart, and means for connecting said bottom with said spring.

In testimony whereof, I have signed this specification in the presence of two subscribing witnesses, this 22d day of July 1907.

GORDON VALENTINE.
